[57] CLAIM

The ornamental design for a computer control panel, as shown and described.

DESCRIPTION

FIG. 1 is a top plan view of a computer control panel showing our new design;

FIGS. 2 and 3 are, respectively, left and right side elevational views thereof;

FIG. 4 is a front elevational view thereof;

FIG. 5 is a rear elevational view thereof;

FIG. 6 is a top, front, right side perspective view thereof.

The keyboard is shown in broken lines in FIGS. 1-6 for illustrative purposes and forms no part of the claimed design.

FIG. I

FIG. 2

FIG. 3

FIG. 4
